FIXTURE FOR STERILE INSTRUMENTS

Leon Jouk, Le Pre Saint-Gervais, France, assignor to
Charles N. Breyner, New York, N. Y.

Application April 5, 1951, Serial No. 219,432

7 Claims. (Cl. 312—223)

This invention relates to cabinets provided with one or more mobile elements, the movement of which is controlled by a photoelectric cell.

More particularly, the invention relates to fixture for sterile instruments such as used for medical purposes in dentistry, otorhinolaryngology, general surgery, appliance for storing dressings and also to cabinets for food products such as used in pastry shops, butcher shops, delicatessen stores.

Such cabinets are provided either with a door or a tray or other mobile element and with photoelectric cell means to control the movement of such mobile element.

The invention described herein covers the fixtures used to enclose the sterile instruments utilized by dentists or surgeons and also refers to the other applications indicated in the above paragraph 2 (for all food industries). The main purpose of this invention is the automatic opening of the cabinet when the practitioner¹ approaches with his hand to take an instrument,² and this happens without it being necessary for him to touch any non-sterile part of the cabinet such as e. g. a handle.

The fixture, according to the invention, includes at least one part which is mobile in relation to the main structure of the fixture and which allows, by being displaced, the access to the sterile instruments contained in the said fixture. This motion is controlled by an electric motor. The fixture also includes means of emitting a pencil of light or infra-red rays (which will be referred to hereunder as "the light beam") which is made to pass in front of the mobile part and then onto a photo-electric cell. The latter is connected with the motor in order to permit displacement of the said part in the direction which allows access to the instruments when the light beam is interrupted and in the opposite direction when the said light beam is reestablished.

Under these conditions, when the practitioner extends his hand to seize an instrument, he interrupts inevitably the light beam and as a result the mobile element moves giving access to the instruments. As soon as he withdraws his hand, after having taken the desired instrument, the light beam is reestablished and the mobile element reassumes its original position.

The mobile element may consist of a drawer or tray having the function of carrying the instruments, and is mounted riding on the main, but also mobile, element. Or it may consist of a door or panel capable of shutting off the space in which are placed the instruments.

In a favorable manner of execution, the fixture would include several riding trays holding the instruments, as well as a retractable panel, preferably of transparent material, placed in front of the trays, this panel being connected to the electric motor in such a manner as to move when the light beam is interrupted and before the trays ride out of the fixture.

Further characteristics of the invention will appear in the complementary description made hereafter with reference to the annexed drawings, given as non-limiting examples, and in which:

Fig. 1 represents, in perspective, a form of execution of this fixture according to the invention;

2

Fig. 2 is a view of an alternate method of execution, also shown in perspective;

Fig. 3 is a vertical section of the fixture in Fig. 2, however, showing it in a closed position;

5 Fig. 4 is a view similar to that given in Fig. 3, the fixture in this case being open;

Fig. 5 is a perspective drawing representing a practical method of carrying out the gearing device which controls the movement of the trays and of the retractable panel;

Figs. 6 and 7 are electrical diagrams showing the connection between the photo-electric cell and the motor; and

Fig. 8 is a schematic drawing of an alternate variant fixture, according to the invention.

15 As represented in Fig. 1, the fixture 1 consists of a recess 2 and is equipped with trays 3 which can ride horizontally and thereby place themselves in this recess. Means, not represented in the drawings, are foreseen to provide permanent sterilization, hot or cold, of the instruments placed on the trays 3.

20 A plate 4 of transparent material such as "Plexiglass" is mounted vertically on the fixture so as to shut off, when it is in a high position, the space wherein are located the trays when these are put back inside the cabinet. The objects and instruments carried by the trays are thus kept isolated from the surrounding atmosphere and consequently are sterile. A projector 5 is provided to send a light beam onto a photo-electric cell 6 after having been reflected on a series of mirrors such as 7. 25 This produces a barrage of light which is necessarily interrupted when one approaches the hand to seize one of the instruments carried by the tray. The recess must be sufficiently deep so that when the trays emerge they do not cut the light beam; if this were to happen, the trays would never reassume their original position. The photo-electric cell 6 e. g. is disposed in such a manner, described hereafter, that when the light beam is cut, this brings about the lowering of the transparent plate 4 and 30 the exit of the trays 3 in the recess, and their return to their original position when the light beam is reinstated.

35 In the alternate variant sample represented in Fig. 2, the fixture does not possess a recess and the optical apparatus is placed a certain distance in front of the fixture so that the trays in their exterior position do not cut the light beam.

40 In this method of execution, the light beam emitted by the projector 5 is transmitted to the cell 6 by the means of two mirrors 7a and 7b.

45 As can be seen in Figs. 3 and 4, the trays 3 are fixed on guiding rails 8 which can ride on horizontal shafts 9 secured at their rear extremity to the body of the fixture. These trays have on each lateral side fingers (or 50 catch pins) 10 which are lodged in grooves 11 found in the connecting rods 12, or in the case of the bottom tray the fingers are attached to the connecting rods. The connecting rods 12 are jointed at their upper extremity, which is free, to small connecting rods 13, these themselves 55 pivoting underneath the upper wall of the cabinet. An electric motor 14 is connected by a belt 15 to a driving pulley 16 the axle of which is connected at each end to a drum 18. On each of these two drums is attached one of the ends of a cable 19 the other end of which is attached to the lower end of plate 4. The diameter of 60 these drums is such that half a rotation corresponds to the necessary displacement of the plate. The drums possess knobs or crank pins 20 which can, when the drums are rotating, engage the fork or prongs fixed to the bottom tray. When the drums assume the position represented in Fig. 3, they make possible the descent of plate 4 by a rotation of 180° and causes the exit of the trays 3, as is seen in Fig. 4. A switch or commutator which is thrown open when plate 4 is lifted to its closed 65 position, is provided to stop the motor when the plate and trays have reassumed their original position.

70 In order to avoid that cables 19 slacken, one can arrange the displacement of trays 3 and panel 4 in the manner ascribed in Fig. 5. A crank 24, with a finger 75 20 at its end, is secured to a shaft 17 fixed to pulleys 16 on each lateral side of the trays. The drums 18 are

¹ Whenever the word "practitioner" appears in this patent, it refers not only to medical practitioners but also to anyone using the cabinet in any field as mentioned in paragraph 2 above.

² Likewise "instruments" can be substituted by objects dealt with in paragraph 2 also.

mounted loosely on the shaft 17 and can be drawn by this shaft by means of lugs 26a on the drums and lugs 26b on the cranks, said lugs each extending over a sector of 90° and said lugs supported by bearings 33.

At the beginning of the rotation of the shaft 17 in the direction of the arrow 25, the lugs 26a make contact with the lugs 26b and as a result of the tension exerted the panel 4 opens itself. When the shaft 17 has rotated 180°, the panel is completely lowered, and the drums stop. The shaft 17 continuing to move, the fingers 20 interweave with the fork 21 and secure the exit of the trays 3. Fork 21 in this case has its slot opening upwardly but said fork is fixed to the lowest tray as in Figs. 3 and 4.

The shaft 17 turning in the opposite direction, as soon as the light beam has been reestablished, the trays 3 return into the cabinet; then, the lugs 26b coming into play with the lugs 26a, the drums 18 are drawn along and the panel 4 returns upwards.

It is clear from the above that the cables 19 do not slacken. In addition, the cranks and the forks are placed at the level of the trays and the whole can be enclosed in an enclosure 32 which is fairly insulating since the only communication with the outside consists of the openings for the shaft 17.

The electric motor 14 should preferably be a series motor, the same being of the type in which a change in direction of rotation can be obtained by reversing the direction of current running through the indicator or field in relation to the current in the armature of the motor.

Referring now to Figs. 6 and 7 there is shown a wiring diagram illustrating the electrical control for motor 14 under the influence of photo-electric tube 6. The terminals 30 are connected to a source of electrical energy 35 (not shown). Armature 28 of motor 14 is connected by lead 146 to one of the terminals 30 and also to switch 23 by lead 46a. Lead 46 connects switch 23 to terminal 42. The other terminal 30 is connected to terminal 43 by lead 47. Terminal 44 is connected to terminal 43 by lead 43a and terminal 45 is connected by lead 48 to switch 22 which in turn is connected to lead 46a by lead 49.

A relay indicated generally by the reference numeral 29 comprises a pair of switch arms 40, 41 pivoted about terminals 27a and adapted to contact either terminals 42, 43 or terminals 44, 45. A reciprocally movable solenoid core 129 is connected to arms 40, 41 and is activated in one direction by a solenoid coil 130 and in the opposite direction by a spring 131 fixed at one end to any convenient stationary position of the device, said portion being indicated schematically at 132.

Terminals 27a are connected to the field coil 27 of motor 14. Solenoid coil 130 is connected at one end to lead 47 by lead 133. The other end of coil 130 is connected by lead 134 to terminal 135 of a conventional amplifier 136, the other terminal 137 of the latter being connected to lead 146 by lead 138. The input terminals 139, 140 are connected to the photo-electric tube 6 by leads 141, 142.

When a hand is interposed to interrupt the beam of light striking photo-electric tube 6, relay coil 130 is de-energized to move switch arms 40, 41 from the position shown in Fig. 6 to that shown in Fig. 7. Switch 23 is open when plate 4 is in its uppermost position closing the cabinet. Movement of plate 4 downwardly will cause switch 23 to open. Switch 22 is closed by the lowermost tray when the cabinet is closed, as shown in the position of Fig. 3, but is opened when the trays move to the open position of Fig. 4. Switches 22, 23 are preferably activated by contact with the lowermost tray and plate 4 in a conventional manner obvious to those skilled in the art.

Fig. 6 illustrates the position of Fig. 3 when the cabinet is closed. In such position switch 23 is open and switch 22 is closed. The circuit through the armature 28 is open because switch 23 is open and the motor therefore is stopped. However, when a hand is interposed in the path of the light ray from the photo electric cell, the circuit to the photo electric cell is open and the relay 29 is de-energized, moving switch arms 40, 41 from the position of Fig. 6 to the position of Fig. 7. The current then flows through armature 28 through wires 46a, 48a, switch 22, wire 43, terminal 45, switch arm 41, inductor 27, switch arm 40, wires 43a and 47. The motor proceeds to move the plate 4 downwardly and to thereafter

move the trays forwardly through the opening in the cabinet. As soon as the plate 4 moves away from switch 23, it closes and when the trays 3 are fully projected, the switch 22 opens itself as shown in Fig. 7, thereby stopping the motor. This position is illustrated in Fig. 7 which now shows switch 22 open.

When the hand is thereafter taken away from its position, interrupting the light through the photo electric cell 6, the circuit to the relay 29 is again completed and the switch arms 40, 41 move back to the position of Fig. 6. At this time switch 23 is closed so that current passes through the inductor 27 in a reverse direction thereby reversing the direction of the motor and causing trays 3 to move back into the cabinet and the plate, to thereafter move up to its closing position of Fig. 4. Such operation again opens switch 23 and closes switch 22, but the opening of switch 23 when the switch arms 40, 41 are engaging terminals 42, 43 prevents any current from passing through inductor 27 and rotation of the motor stops.

It is understood that one can, without diverging from the basic frame of the invention, modify the details of the manners of execution of the fixture as described above. Thus, e. g. plate 4, instead of moving up and down, could be mounted pivoting around a horizontal axis, as is shown in Fig. 8. The control of the trays and the plate or in general of the mobile element, could be carried out by means of an eccentric axle, a cam, levers or entirely different devices. One could plan a hand-operated crank, to obscure the photo-electric cell or the projector when the drawers are open, in order to maintain this position.

Having thus described my invention, I claim as new and desire to secure by Letters Patent:

1. In combination, a cabinet formed with an opening, a panel to close said opening, a tray movably mounted within said cabinet and movable through said opening, an electric reversible motor, means controlled by the motor to open the panel and thereafter to move said tray through said opening upon rotating the motor in one direction and to retract said tray into the cabinet through said opening, and, thereafter close said panel upon rotating said motor in an opposite direction and photo-electric cell means to control the direction of rotation of said motor and including means to project a beam adapted to be interrupted by movement of an operator's hand adjacent said cabinet.

2. In combination, a cabinet formed with an opening, a panel slidably relative to the cabinet to positions covering and uncovering said opening, a plurality of trays slidably mounted within said cabinet one above the other and movable through said opening when it is uncovered, an electric motor within the cabinet, means controlled by said motor to slidably move said panel from covering to uncovering position and to thereafter move said trays through said opening so as to project from said cabinet upon rotating said motor in one direction and to first retract said trays into said cabinet and thereafter move said panel back to covering position upon rotating said motor in an opposite direction, photo-electric cell means to control the direction of said motor including means to project the light beam exteriorly of the cabinet and means to receive said light beam whereby the hand of the operator moving across the beam will interrupt the beam.

3. In combination, a cabinet formed with a front opening, a panel slidable up and down at the front of the cabinet to close and open said opening, a plurality of trays slidably mounted within said cabinet, a slotted link interconnecting said trays, a disk rotatably mounted within the cabinet, electric motor control means to rotate said disk, a pin on said disk, a fork on one of said trays engageable with said pin and a cable interconnecting said disk with said panel.

4. In combination, a cabinet formed with an opening, a panel to close said opening, a tray within said cabinet and movable through said opening, an electric motor within said cabinet, means controlled by said electric motor to first open the panel and then project the tray through said opening upon rotating said motor in one direction, and for retracting said tray into the cabinet and then closing said panel upon rotating said motor in an opposite direction and photo-electric cell means to control the operation of said motor.

5. The combination of claim 4, in combination with means to automatically stop the operation of said motor

after projection of said tray and after the closing of said panel, respectively.

6. The combination of claim 4, said photo-electric cell means, including means to project a light beam adapted to be interrupted by movement of the operator's hand adjacent the cabinet.

7. In combination, a cabinet formed with an opening, a panel to close said opening, a tray within said cabinet and movable through said opening, an electric motor within said cabinet, means controlled by said electric motor to first open the panel and then project the tray through said opening upon rotating said motor in one direction, and for retracting said tray into the cabinet and then closing said panel upon rotating said motor in an opposite direction, and photo-electric cell means to control the operation of said motor, means to automatically stop the operation of said motor after projection of said tray and after the closing of said panel, respectively, said photo-electric cell means including means to project a light beam adapted to be interrupted by movement of the operator's hand adjacent said cabinet.

cally stop the operation of said motor after projection of said tray and after the closing of said panel, respectively, said photo-electric cell means including means to project a light beam adapted to be interrupted by movement of the operator's hand adjacent said cabinet.
